UNITED STATES PATENT OFFICE.

JOHN ELWOOD MORRISON, OF BALTIMORE, MARYLAND.

DESIGN FOR LAUNDRY-WAX FOR SAD-IRONS.

SPECIFICATION forming part of Design No. 22,925, dated November 28, 1893.

Application filed May 6, 1893. Serial No. 473,302. Term of patent 3½ years.

To all whom it may concern:

Be it known that I, JOHN ELWOOD MORRISON, a citizen of the United States, residing at Baltimore, in the State of Maryland, have invented and produced a new and original Design for Laundry-Wax for Sad-Irons, of which the following is a specification.

This invention relates to a new and original design for laundry-wax for sad-irons.

10 In the accompanying drawing in which the design is illustrated, the letter A indicates a spherical body portion, and B a conical cup-shaped piece secured to the spherical body, the said cup having the appearance of em-

bracing a part of the said spherical body portion. A handle, C, has a slim shank, c, which is attached to the apex of the cup-shaped piece. 15

Having thus described my design, I claim—

The design for laundry-wax for sad-irons 20 substantially as described and shown.

In testimony whereof I affix my signature in the presence of two witnesses.

JOHN ELWOOD MORRISON.
